UNITED STATES PATENT OFFICE.

TIMOTHY KELLACKEY, OF CLEVELAND, OHIO.

PIPE-THREADING DIESTOCK.

Application filed August 8, 1924. Serial No. 730,820.

The present invention, relating, as indicated, to die stocks is more particularly directed to a pipe threading die stock provided with means for automatically releasing the dies on completion of the threading operation. A further object of the invention is the provision of an extremely simple and efficient mechanical means operable upon the completion of the threading operation and engaged by the stock being threaded when the latter has reached a predetermined position for resetting the threading members. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—

Fig. 1 is a plan view of my improved die stock; Fig. 2 is a similar view with a portion of the mechanism removed; Fig. 3 is a similar view with the cover or end plate of the stock removed; Fig. 4 is a plan view of the setting handle and cam; Fig. 5 is a section on the line 5—5 in Fig. 3; Fig. 6 is a transverse vertical section through the setting mechanism; Fig. 7 is a section on the line 7—7 in Fig. 6; and Fig. 8 is a section on the line 8—8 in Fig. 1 showing a guide means for the dies 2.

The die stock proper consists of two spaced annular members 1 and 2, in each of which are mounted in radial position a series of threading members or dies 3, shown in Figs. 1, 2 and 3, these members being radially movable upon the rotational movement of an operating member or cam plate 4 mounted upon the upper member 1. This cam plate 4 is provided with a series of cams engaging in slots 7 in the die members 3, the engagement being such that rotation of the cam plate will produce inward or outward radial movement of the die members, depending upon the direction of rotation of the cam plate, and this movement will be equal for all of the several die members.

Mounted in a boss 8 of die case 4, formed as a part of one of the handles 9 of the

member 1, is a shaft 10, which is provided at its lower end with a locking handle 11. This shaft is bodily movable circumferentially of the die in the slot 12 formed in the boss, and may be set in any position in the slot by turning the handle 11 to screw down the shaft 10 and bring a plate 13 on the upper end of the shaft into engagement with the upper surface of the boss 8. The rotatable cam plate 4 is provided with an extension extending over the boss 8 and slot 12, in which is formed an oval opening 14 having its long dimension lying radially of the die. Mounted in this opening is a circular member 15 provided with an enlarged head portion 16 and handle 17. The portions 15 and 16 are provided with circular openings fitting over the shaft 10, these openings being in alignment and being eccentric to the center of the members 15 and 16 so that rotation of these parts, by moving the handle 17, will cause the lower portion 15 to act as a cam and rotate the cam plate 4. The member 15 is normally maintained in a position holding the cam plate in its limiting position outward, that is, holding the die members 3 in their retracted position by means of a coil spring 18, one end of which engages in a hole formed therefor in the member 15, while the other end of the coil spring engages in a corresponding hole formed in a retaining member 20 formed with a polygonal opening therein which fits over a similarly formed portion on the shaft 10, while a lock nut 21 maintains the retaining member 20 in such engagement on the shaft.

The cam plate is caused to return to its retracted position and to cause the dies to move out of engagement with the stock when the stock has reached a predetermined position by the following means. Extending inward into the path of movement of the stock is a lever 22, which is rigidly connected to an arm 23, (see Fig. 5), the latter arm being pivoted about an axis 24 and connected at its lower end to a second arm 25 having a movable connection with a vertically disposed locking pin 26. The latter is provided with a beveled upper end, which fits into a corresponding notch 27 in the member 15, and normally maintains the members 15 and 16 in the desired position. When the stock engages the end of the member 22, however, and swings this member 110

about its axis, the locking pin 26 is retracted from its engagement with the member 15 and the coil spring 18 then acts to rotate the members 15 and 16 and in this way to swing the cam plate to its original position, releasing the die. The tension on the spring 18 may be adjusted by turning down the lock nut 21, thus coiling the spring and increasing the tension.

10 The latch member 26 is normally pressed upward into engagement with the recess in the member 15 by means of a coil spring 28 mounted as shown in Figs. 5 and 6 and operating at its upper end against a shoulder 29 formed on the rod 26.

In Fig. 8, I have shown the mounting of the dies 3 in the member 1 and in the cam plate 4. The cam plate is provided with a series of downwardly extending flanges 30 20 engaging against the upper surface of the dies 3 and preventing tipping of these dies during their inward and outward movement as the die is then borne on the flat lower bed or guide surface of the member 1 and against 25 the engaging flange 3 on the cam ring or disk 4.

In Fig. 1, I have shown graduations 32 formed on a removable cover plate 33 on the member 1 with a single graduation 35 on the cam ring 4 enabling the user to set the dies to both the normal position and to graduations from the normal to compensate for oversize or undersize heads which it is desired to cut upon the stock.

Other modes of applying the principle of my invention may be employed instead of the one explained, change being made as regards the mechanism herein disclosed, provided the means stated by any of the following claims or the equivalent of such 40 stated means be employed.

I therefore particularly point out and distinctly claim as my invention:

1. In a die stock, the combination of a die head, a plurality of dies radially movable in said head, means normally maintaining said dies in operative position in engagement with a blank, said means including a rotatable ring engaging said dies and having an opening therein, a cam mounted in such opening, and means operable by a blank within said dies for causing actuation of said cam to move said ring.

2. In a die stock, the combination of a die head, a plurality of dies radially movable in said head, means normally maintaining said dies in operative position in engagement with a blank, said means including a rotatable ring engaging said dies and having an opening therein, a cam mounted in such 50 opening, and means for adjusting said cam to variously position said ring and said dies, and means operable by a blank within said dies, said means causing operation of said cam.

Signed by me, this 31st day of March, 1924.

TIMOTHY KELLACKEY.
